(57) **CLAIM**

The ornamental design for a LED strip light assembly, as shown and described.

DESCRIPTION

FIG. 1 is a perspective view of a LED strip light assembly showing the claimed design with one component removed for clarity of disclosure;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of the LED strip light assembly showing the plug for the light removed for the clarity of disclosure;

FIG. 10 is another perspective view of the plug for the light thereof;

FIG. 11 is a front elevational view of the plug for the light thereof;

FIG. 12 is a rear elevational view of the plug for the light thereof;

FIG. 13 is left side view of the plug for the light thereof;

FIG. 14 is right side view of the plug for the light thereof;

FIG. 15 is a top plan view of the plug for the light thereof;

FIG. 16 is a bottom plan view of the plug for the light thereof;

FIG. 17 is an enlarged view for FIG. 9 thereof;

FIG. 18 is an enlarged view for FIG. 10 thereof; and,

FIG. 19 is a perspective view of the LED strip light assembly showing the claimed design.

The broken lines depict portions of the LED strip light that form no part of the claimed design.

The dot-dash lines surrounding the detail views are for annotative purposes only and form no part thereof. Additional broken lines shown in FIG. 19 depict environment only and form no part of the claimed design.

1 Claim, 19 Drawing Sheets
